CONNECTOR

George D. Rogers, United States Army,
Washington, D. C.

Application April 18, 1941, Serial No. 389,190

1 Claim. (Cl. 85—5)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to devices of the type used for temporarily securing together articles such as plates preparatory to the riveting or other permanent fastening thereof.

This invention has as an object the provision of an improved device for aligning and securing holed plates to each other.

It is a further object of the invention to provide a connector which can be operated with one hand in restricted spaces and in spaces where the back of the work to be secured is inaccessible.

Another object of the invention is to provide a connector having means to secure positive alignment of the parts to be connected.

A still further object of the invention is to produce a connector by means of which connecting pressure can be applied symmetrically about the periphery of the holes in the plates for securing the plates to be connected without distortion or straining thereof.

The specific nature of the invention as well as other objects and advantages thereof will clearly appear from a description of a preferred embodiment as shown in the accompanying drawing in which:

Figure 1 is an elevational view of the device of this application.

Figure 2 is a vertical section of the device at one stage of its operation taken on the line 2—2 of Figure 1.

Figure 3 is a view similar to that of Figure 2 taken at another stage in the operation of the device.

Figure 4 is a side elevation of the bolt member.

The connector comprises a bolt member 3 hollow for the greater portion of its length and adapted to be inserted through apertures 4 and 5 formed respectively in plates 6 and 7. The bolt member 3 is split longitudinally from its lower end to allow for expansion and provided with an enlarged head 8 having shoulders 9 adapted to engage the surface of the plate 7 surrounding the aperture 5. The bolt member is provided at its other end with a flange 10 adapted to engage a spring 11. The longitudinal expansion splits above referred to are formed by a plurality of radial cuts extending longitudinally from the head end to near the flanged end as best seen in Figure 4. The upper portion of the flange 10 is provided with two or more upstanding seg-

mental setting members 12 for a purpose as will hereinafter appear.

The bolt member is contained in a case 13 having a base 14 adapted to engage the upper surface of the plate 6 and having an aperture 15 through which the head 8 protrudes. Between the flange 10 and base 14 is inserted a spring 11 tending to draw the head 8 within the case 13. At its upper portion the case 13 is provided with a cover 16 having apertures 17 formed therein for the reception of the segmental setting members 12. The cover 16 is also centrally provided with an inwardly extending pin 19 inserted into the axial passage in the bolt member 3. The pin 19 is provided at its lower end with a tapering portion 20 adapted to engage cooperating surfaces 21 at the lower end of the axial passage in the bolt member. As the bolt member is drawn within the casing under the influence of the spring, the tapering portion of the pin will expand the split shank of the bolt member owing to the wedge action between cooperating surfaces 20 and 21. The relative dimensions of the parts to be secured govern the length and diameter of the bolt member and expanding pin.

30 The connector is applied in practice by grasping it with a special tool 2 which engages the flange 18 and the setting members 12 as shown in Fig. 1 and serves to compress the spring 11. Owing to the resiliency of the material of which 35 the bolt member is constructed the head 8 will contract to its minimum diameter and in this condition it is inserted into the holes 4 and 5 in the plates 6 and 7, as shown in Fig. 2. Upon removal of the tool 2 the head 8 will be expanded, 40 as shown in Fig. 3, serving to properly align the holes and the shoulders 9 will on engaging the surface of the plate 7 serve to draw it firmly into contact with plate 6. This contact will be maintained at spring pressure until the connector is 45 withdrawn and while the plates are thus temporarily secured permanent fastening means may be inserted in adjacent holes which likewise will have been drawn into alignment or necessary plate fitting operations may be carried out. The device may be removed by again grasping it with the tool 2 and recompressing the spring upon 50 which the head will contract and can be readily withdrawn from the work.

It is to be understood that the form of my invention specifically shown and described is to be

taken as a preferred example of the same and that various changes in the size and arrangement of parts may be resorted to without departing from the spirit of my invention as described in the appended claim.

I claim:

A device for securing superposed perforated plates comprising a bolt member having a head on one end, said bolt member having a plurality of radial cuts extending longitudinally from the head end to near the opposite end and a spring engaging flange formed on said last mentioned end, an axial passage in said bolt member intersecting the radial cuts and extending to the end opposite the head, upstanding setting members 15

on the face of said flange away from said head, a substantially cup-shaped casing containing the bolt member and having a bore in its bottom wall through which the head protrudes, a compression spring interposed between the flange and the inner bottom wall of the casing, a cover secured on the open end of said cup-shaped casing, said cover being formed with openings therethrough for the passage of said setting members, and a wedge member secured to said cover and thereby supported in the axial passage, said wedge member being adapted to cause the head to expand radially.

GEORGE D. ROGERS.
